UNITED STATES PATENT OFFICE.

GEORGE W. MURPHEY AND FRANK P. MURPHEY, OF KENNEY, ASSIGNEES
OF TWO-FIFTHS TO PARK B. MURPHEY AND CHARLES M. MURPHEY,
BOTH OF HARRISTOWN, ILLINOIS.

AUTOMATIC FIRE-ESCAPE.

SPECIFICATION forming part of Letters Patent No. 297,620, dated April 29, 1884.

Application filed June 14, 1883. (No model.)

To all whom it may concern:

Be it known that we, GEO. W. MURPHEY and FRANK P. MURPHEY, residents of the town of Kenney, county of De Witt, and State of Illinois, have invented certain new and useful Improvements in Automatic Fire-Escapes, of which the following is a specification, sufficiently full, clear, and exact to enable any one skilled in the art to which it relates to make and operate the same.

Our invention relates to that class of automatic fire-escapes in which a cord and pulley are used for lowering purposes.

In the drawings accompanying and forming a part of this specification, Figure 1 is a front view of mechanism that illustrates the principle of our invention, and Fig. 2 is a sectional view of Fig. 1 on dotted line *xx*.

m is the pulley, around which cord *i* is wound.

b is a cog-wheel rigid on the shaft of pulley *m*.

c is a pinion that receives motion from wheel *b* and imparts the same, through rack and pinion *d g*, to the oscillating wheel *a*.

f is a crank-pin on *c*, that connects with and operates rack *d*. Rack *d* is provided with a slot that works on the shaft and holds the rack-teeth in gear with the pinion. Pinion *g* and wheel *a* are rigid one with the other, and both work loosely on their shaft. *h* provides a point of attachment for a belt or other lowering device. A pintle will be formed on the shaft of pinion *c* to receive a key to wind up the cord.

In actual use the gearing should be inclosed and more compactly arranged, while the form of the casing *e* is modified to conform to such modification.

The cord may be attached to an opening in the burning building and the escaping person descend with the pulley; or the pulley may be attached and the operation reversed. As the cord unwinds, the rotating motion of the pulley is conveyed through *b* to pinion *c*, where it is converted into oscillating motion in rack *d g* and imparted as such to pinion *g* and wheel *a*.

It will be readily perceived that the power required to reverse the motion of wheel *a* will greatly retard the motion of the pulley, and after the proper proportion in the gearing is once obtained any variation in the weights of persons descending on the cord will not perceptibly affect the speed of the descent, as the swifter the motion of the oscillating wheel the greater will be the power required to reverse the motion thereof.

We claim—

In an automatic fire-escape, the combination of a cord-pulley, a gear-wheel, a crank-pinion, a rack and pinion, and an oscillating lever, as and for the purpose set forth.

GEO. W. MURPHEY.
FRANK P. MURPHEY.
